UNITED STATES PATENT OFFICE

115,666

DESIGN FOR A PLATE OR SIMILAR ARTICLE

Edgar Mott Bottome, Moundsville, W. Va., assignor to Fostoria Glass Company, Moundsville, W. Va., a corporation of West Virginia

Application April 17, 1939, Serial No. 84,334

Term of patent 3½ years

To all whom it may concern:

Be it known that I, Edgar Mott Bottome, a citizen of the United States of America and resident of Moundsville, county of Marshall, and State of West Virginia, have invented a new, original, and ornamental Design for a Plate or Similar Article, of which the following is a specification, reference being had to the accompanying drawing, forming part thereof, in which—

The single figure is a bottom plan view of a

plate or similar article, showing my new design, one-half of the plate or similar article being defined by dotted lines, it being understood that the surface ornamentation is repeated throughout the entire circumference of the plate.

I claim:

The ornamental design for a plate or similar article, substantially as shown and described.

EDGAR MOTT BOTTOOME.
